UNITED STATES PATENT OFFICE.

BEVILL W. WHITWORTH, OF OMAHA, NEBRASKA.

ADJUSTABLE SHADE SUPPORT.

Application filed June 6, 1924. Serial No. 718,249.

The invention relates to adjustable shade supports, and has for its object to provide a device of this character comprising weight members slidably mounted on parallel rods 5 on opposite sides of a window frame, and provided with means for receiving pintles of a shade. One of the parallel rods of one side of window is rotatably mounted within the adjacent weight member, and has its 10 upper end provided with a gear connection with a horizontally disposed drum carrying shaft, which shaft is provided with drums over the weight members, and with flexible connections between the drums and weight members whereby upon rotation of the rotatable parallel rod, the weight members will be simultaneously raised or allowed to lower.

A further object is to provide a rotatable bevelled gear in a casing adjacent the lower 20 end of the rotatable parallel rod and which bevelled gear meshes with a bevelled gear carried by said rod; said first mentioned bevelled gear being provided with means for receiving a wrench for rotating the same.

With the above and other objects in view the invention resides in the combination and arrangement of parts as hereinafter set forth shown in the drawing, described and claimed, it being understood that changes in 20 the precise embodiment of the invention may be made within the scope of what is claimed without departing from the spirit of the invention.

In the drawing:—

Figure 1 is an enlarged front elevation of the device, showing the same applied to facings of a window frame, and the covers removed from the casings of the device to better illustrate the structure.

Figure 2 is a top plan view of one of the weight members.

Figure 3 is a perspective view of the device showing the same applied to a conventional form of window frame.

Figure 4 is a detail sectional view taken on line 4—4 of Figure 1.

Figure 5 is a modified form of gear drive for the horizontally disposed drum shaft, showing worm gears.

Referring to the drawing, the numeral 1 50 designates a conventional form of window frame and 2 the facings at opposite sides thereof. Secured to the facings 2 adjacent their lower ends are casings 3 and 4, which casings are connected to casings 5 and 6

adjacent the upper ends of the facings 2 by means of parallel rods 7 and 8, which are vertically disposed. The rods 7 have their ends provided with nuts 9 for rigidly holding the same, however the rod 8 is rotatably mounted in bearings 10 of the casings 4 and 6, and has its lower end provided with a bevelled gear 11, with which a bevelled gear 12 carried by a horizontally disposed shaft 13 meshes. It will be seen that when a 60 socket wrench is placed in the socket 14 in the outer end of the bevelled gear 12, and the bevelled gear and shaft rotated, the vertically disposed rotatable rod 8 will be rotated. Rotatably mounted in bearings of 70 the casings 5 and 6 adjacent the upper end of the window frame is a horizontally disposed shaft 15, which shaft is provided with a bevelled gear 16 disposed within the casing 6, and which bevelled gear meshes with a 75 bevelled gear 17 carried by the upper end of the rod 8, consequently when the rod 8 is rotated the shaft 15 is also rotated. Secured to the shaft 15 are drums 18, which drums have secured thereto as at 19 flexible members 20 which extend downwardly through the undersides of the casings 5 and 6 and are secured at 21 to rings 22 carried by the upper ends of slidable weight members 23, which are slidably mounted on the rods 7 85 and 8. However it will be seen that the rod 8 is rotatably mounted within one of the weight members, but at the same time it forms a guide for weight member in its vertical movement, therefore the use of a 90 separate operating shaft is obviated. Weight members 23 are provided with arms 24 for the reception of the pintles 25 of a shade roller 26, and consequently when said weight members 23 are simultaneously 95 raised by the rotation of the drums 18 or allowed to lower under their own weight, the shade roller may be positioned at various elevations, and particularly to a position where the upper sash of a window may 100 be lowered and a free passage of air allowed to a room without interference from the shade 27.

Referring to Figure 5, the device is substantially the same as shown in Figure 1, 105 with the exception that the casing 6^a has disposed therein helical or worm gears 28 and 29 instead of the bevel gears 17 and 16, and this form is particularly adapted where the casings 6^a are secured to the inner face of a 110

window frame, otherwise the construction and operation is the same as shown in Figure 1.

From the above it will be seen that an adjustable shade support is provided, which is simple in construction, positive in its operation and provided with gear operating mechanism, which gear operating mechanism will require sufficient power to operate the same, which will be greater than the power of the weights 23 and therefore the weights will stay in any position to which they may be moved. The various casings and weights are preferably formed in sections so that they may be easily and quickly assembled on the rods, and access may be easily and quickly had to the casings.

The invention having been set forth what is claimed as new and useful is:—

20 1. An adjustable shade supporting means comprising casings secured to the opposite sides of a window frame adjacent the upper and lower ends thereof, parallel vertically disposed rods connecting said casings, weight members vertically slidable on said rods, shade pintle receiving members carried by said weight members, a horizontally disposed shaft rotatably mounted in the upper casings, drums carried by said horizontally disposed shaft, flexible members extending around said drums, said flexible members having their ends secured to the weight members, one of said vertically disposed rods being rotatably mounted in the casings and 35 in the weight member, gear connections between said last named rod and the hori-

zontally disposed rod, a gear rotatably mounted in one of the lower casings, said last named gear meshing with a bevelled gear carried by the lower end of the rotatable rod 40 and means whereby the gear mounted in the lower casing may be rotated.

2. The combination with an adjustable shade supporting device, said device comprising vertically disposed parallel rods at 45 opposite sides of the window frame, weight members slidably mounted on said rods, a horizontally disposed rod at the upper end of the frame and rotatably mounted, cable connections between the weight members and the horizontally disposed rods, of means for rotating the horizontally disposed rods, said means comprising gear connections between the horizontally disposed rod, and the upper end of one of the parallel rods and bevel gear 50 means cooperating with the lower end of said last named rod.

3. The combination with an adjustable shade roller supporting device, said device comprising weight members slidably mounted on parallel rods, a drum rod, flexible connections between the drum rod and the weight member, of operating means for the drum rod, said means comprising one of the parallel rods, gear connections between the 60 drum rod and last named parallel rod and means for rotating said last named parallel rod.

In testimony whereof I hereunto affix my signature.

BEVILL W. WHITWORTH.
